UNITED STATES PATENT OFFICE.

CARL ROEHL, OF DAVENPORT, IOWA, ASSIGNOR OF ONE-HALF TO CARL FR. KLENZE, OF SAME PLACE.

ADJUSTABLE HAME.

SPECIFICATION forming part of Letters Patent No. 285,841, dated October 2, 1883.

Application filed January 10, 1883. (No model.)

To all whom it may concern:

Be it known that I, CARL ROEHL, of Davenport, in the county of Scott and State of Iowa, have invented certain new and useful Improvements in Adjustable Hames; and I do hereby declare that the following is a full, clear, and exact description thereof, reference being had to the accompanying drawings, and to the letters of reference marked thereon, which form a part of this specification.

This invention relates to that class of horse-collars which are composed of several parts, adjustably connected together in such manner that the size of the collar can be increased or diminished, as desired; and the invention consists in a metallic hame that is adjustable in every direction to adapt the same to fit collars of different size and shape and the necks and shoulders of different horses.

The hame, which is designed as an improvement on the devices shown in my former patents, dated August 16, 1881, Nos. 245,869 and 245,870, is of metal and formed in sections, and at its upper part is hinged and laterally adjustable, vertically adjustable at or about the center, laterally adjustable and provided with a socket-and-tenon connection and a hinged spring locking device at its lower end, and has vertically-adjustable tug and martingale eyes, and means for securing the hame within the crease of the collar, all as hereinafter described and claimed.

In the drawings, Figure 1 represents an elevation of the hame with the parts in locked position. Fig. 2 is a section through the lower laterally-adjustable and locking portion, showing the parts unlocked. Fig. 3 is an elevation of one member of the hinged locking-tube. Fig. 4 is an elevation of the other member of the hinged locking-tube. Fig. 5 is a section of the upper portion of the hame, showing the lateral adjustment. Fig. 6 is a sectional detail view of the vertical adjusting parts of the hame. Fig. 7 is a cross-section on the lines $x-x$ of Fig. 6, and Fig. 8 is a cross-section showing the manner of securing the adjustable tug and martingale loops or eyes.

A represents the upper, and L the lower, sections of the hame. The lower end of each upper bar, A, is slotted at I, and is placed against the upper portion of the lower bar, L,

and under a cap-plate, t, that is riveted to bar L, where it is adjustably secured by an eye-headed screw, m, which is passed through a hole in cap-plate t and is tapped into such lower bar L. This bar L has a grooved or flanged upper extremity, p, that assists in guiding and holding the bar A and L in line with each other.

The upper portion of bars A A is curved and tapering, and is slotted at a, and is passed through end loops, q, of extension-plates M M, that are correspondingly curved, and are provided each with a cap-plate, B, which covers the slotted portion a of bar A, and an eye-headed screw, e, is tapped into plate M, and is passed through a hole in cap-plate B and through the slot a of bar A in a manner to draw the plates M and B together and to clamp the slotted portion of bar A between. These plates M have hinge-eyes formed to their upper extremities, where they are pivotally connected by a pin, b, the eyed head of which holds a ring, N.

Against the lower extremity of each bar A is screwed or riveted a curved extension plate, O, that has a longitudinal depression or groove, and is covered by a curved cap-plate, C, secured thereto by a screw, d.

D and E represent pieces having a slotted rear end, e and h, which are inserted between the extension O and cap-plates C, and an eye-headed screw, f or i, is passed through a hole in such cap-plate C and through the slot e of piece D or E, and is tapped into one of the plates O in a manner to draw such cap C and plate O together, and thus form a clamp for adjustably securing the piece D or E between. At its forward end the piece D has a socket, g, and the piece E a tenon, j, which, when the hames are brought together, enters the socket g, and thereby connects the two lower ends of the hames and holds them steady. For the purpose of securing and locking the free lower ends together a tube, F, is hinged by a turn-bolt, K, to one extension-piece, D, and a tube, G, to the other extension-piece, E. The tube G is of a diameter to enter tube F, and carries a turn-bolt, H, that at either end has a flat head, l l', and is surrounded by and connected with one end of a spiral spring, s, which, with its opposite end, is secured to tube G in

a manner to resist the turning of such bolt H. When it is desirable to lock the hames together, the bolt H is rotated a quarter-turn, while the tube G is pushed within the tube F until the head l' emerges from the opposite end, when, with releasing the bolt, it will be turned by the spring to its original position, which will place the head l' across the slotted end of said tube F, whereby it will lock the two members of the locking device, and consequently the hames, securely in position, the spring s preventing the turn-bolt from uncoupling on its own accord.

The end opening of tube F is of an elongated form, as shown in Fig. 4, to admit of the head l' readily passing therethrough while in one position, but preventing its return when turned partly around. The tubes F and G being pivotally secured to extension-pieces D and E, they can accommodate themselves to be in line with each other with every adjustment of the hames.

P P represent the terrets, that are screwed or riveted to hame-bars A. At about its middle each hame-bar L has a grooved or recessed portion, that is provided with a flange, u, against which a curved guard-plate, Q, and a cap-plate, o, are secured by riveting. The tug-eye R forms part of a slotted plate, v, that is placed in the groove under cap-plate o, and an eye-headed screw, n, is passed through a hole in such cap-plate and through the slot of plate v, and is tapped into bar L in a manner that such tug-eye plate can be shifted up or down, and is secured in any desired position by tightening screw n, and thereby clamping the slotted plate v between bar L and cap-plate o. The breast-strap rings or martingales J are connected by eye-screws, that are screwed into such tug-eye plate. The traces, being coupled to the tug-eyes, will lean against plates Q, that will protect the collar or pad against rubbing and chafing.

K K represent bolts, which are passed through the collar with their flat T-heads resting against the inside thereof, for the purpose of securing the hames within the crease of the collar.

As will be noticed, by set-screws e the upper hinged portion of the hames can thus be laterally expanded or contracted; by set-screws m the hames can be elongated or shortened vertically, and by set-screws i and f the lower or locking portion of the hames can be expanded or contracted, each independently of the other, in a manner to adjust such hames to fit any collar, or to bring and hold such collar to the desired size and form that will best fit the neck and shoulder of the horse.

60 In a like manner can be adjusted the tug-eye to a higher or lower position, most suitable for the horse to pull its load, thus providing hames for use with horses of different sizes and shapes, in which the several parts are securely locked in position in a simple manner and with great readiness.

I claim—

1. Sectional metal hames, having curved and tapering upper bars, A, slotted at their upper and lower ends, curved extension-plates M, hinged together at b, and having end loops, q, cap-plates B, and screws c, the lower bars, L, having flanged upper extremity, p, cap-plate t, screws m, curved extension-plates O, curved cap-plates C, screws d, and the hinged 75 spring locking device herein described, substantially as and for the purpose set forth.

2. The combination, with the curved slotted bars A, of the curved extension-plates M, having end loops, q, cap-plates B, and screws 80 c, substantially as and for the purpose set forth.

3. In metal hames, the hinged extension-plates M, with caps B and clamp-screw c, in combination with the hame-sections A, having slotted upper ends, substantially as and for the purpose set forth.

4. The hame-sections L, arranged to form adjustable connection with piece D, having socket g, and with piece E, having tenon j, 90 substantially as and for the purpose set forth.

5. The metal hames L, having plates O, caps C, and clamp-screws f i, in combination with piece D, having slotted end e and socket g, and of piece E, having slotted end h and 95 tenon j, all substantially as and for the purpose set forth.

6. The metal hames provided at their lower ends with a locking device, consisting of tubes F and G, that are pivotally connected to such hames, and are adapted to be locked together by a turn-bolt, H, substantially as and for the purpose set forth.

7. The combination, with the hames, of a slotted and socketed piece, D, the slotted and tenoned piece E, and the pivotally-connected locking device F G H, substantially as and for the purpose set forth.

8. In combination with the hames, the pivotally-connected locking device, composed of tube G, with turn-bolt H, and spring s, and of tube F, all constructed and arranged substantially as and for the purpose set forth.

9. The combination, with grooved bar L, having flange u, of the cap-plate o, slotted 115 plate v, screw n, and the tug and martingale eyes R J, all constructed and arranged substantially as and for the purpose set forth.

10. The combination, with the grooved hame-section L, cap o, and clamp-screw n, of 120 tug-eye R, having slotted plate v, all substantially as and for the purpose set forth.

11. A hame having T-headed bolts K, for the purpose of securing said hame within the crease of a horse-collar, substantially as set 125 forth.

In testimony that I claim the foregoing as my invention I affix my signature in presence of two witnesses.

CARL ROEHL.
